his ATTORNEY

UNITED STATES PATENT OFFICE

WILLIAM A. FRANK, OF HACKENSACK, NEW JERSEY, ASSIGNOR TO NATIONAL WATER MAIN CLEANING CO., OF NEW YORK, N. Y., A CORPORATION OF MAINE

PIPE CLEANING MACHINE

Application filed February 25, 1930. Serial No. 431,087.

This invention relates to a machine for cleaning the scale and other deposits from the interior wall of a pipe and has particular application to a water main in which a head of water is maintained and utilized as the propelling agent for the machine.

Pipe cleaning machines of this character operating under ordinary conditions scrape the interior surface of a pipe and permit the removed incrustations and other foreign matter to accumulate in front of or ahead of the machine with a result that the travel of the latter is materially obstructed and the machine itself is lifted to the upper portion 15 of the pipe.

With the foregoing in mind, it is the purpose of the present invention to afford means embodied in the construction of the cleaning machine whereby the matter being removed is caught in the whirling head of water traversing the main and held in suspension so as not to interfere with the proper travel and uniform cleaning action by the machine.

I accomplish this purpose by means of the device hereinafter described in the specification, set forth in appended claims and illustratively exemplified in the accompanying drawing, in which Figure 1 is a substantially longitudinal sectional view taken through the cleaning machine disposed within a water main; Figure 2 is an elevational view of the leading end of the machine showing parts broken away to disclose otherwise hidden elements; and Figure 3 is an elevational view of the other or trailing end of the machine.

Referring to the drawing in detail, 10 designates a pipe, preferably a water main in which a head of water is maintained in the direction of the arrow outside the pipe. The cleaning machine comprising the present invention is propelled through the pipe by the head of water which is diverted in the ma-

chine itself to cause a rotary movement as well as a longitudinal movement thereof.

The cleaning machine is constructed in two sections, the leading section A and the trailing section B. The leading section A comprises a tubular portion 11 having its forward end flared outwardly and provided with curved vanes 12 to cause the machine to rotate about its axis and that of the pipe as a center. The action of the head of water 50 is to drive the machine forward causing the latter to rotate slowly. The vanes 12 are integral with the wall of the flared portion of the tube 11 and are provided with a cover 13 of conical shape and integral about its outer periphery or base with a guide cone 14 which is truncated on a plane parallel with the base. The cover 13 is held in place by means of nut 15 seated against the inner surface of the apex of the cone. The nut 55 15 is arranged on the threaded mid portion of a double eyed link 16, the inner eye of which receives the loop end of a cable 17. The opposite end of the cable 17, which extends axially through both sections A and B, 60 is projected through a tubular casing 18 and is turned upon itself to form a loop 19 and maintained in position by a clamp block 20. The block 20 slides axially in the tubular casing 18 which is closed at its forward end to 65 provide a seat for one end of a spring 21, the opposite end thereof abutting the block 20. The spring 21 is housed in the casing 18 and tends not only to maintain the cover 13 in position over the blades or vanes 12, 70 but it likewise holds the two sections A and B in line by means of an articulated coupling 22 through which the cable passes between the two sections.

The tubular casing 11 is provided with leakage holes 23 spaced from each other circumferentially of the casing and capable of being closed by a sleeve valve 24 slidably mounted in guide blocks 25 on the interior face of the casing. The adjustment of the sleeve valve 85 24

24 with respect to the holes 23 determine the amount of water allowed to leak through the forward blades of the machine.

The spring casing 18 is externally threaded 5 to receive a threaded collar 28, which turns against a spider connection 27 at the trailing end of the second section B, and which is adjustable over the casing to alter the position of the latter and consequently to change the 10 tension of the spring 21. The casing is further provided with a spline or keyseat 26 into which a key or projection of the spider connection 27 is arranged to prevent turning thereof when the collar is turned.

15 Both sections A and B are made up of a plurality of scraper heads 29 which are annular members, each thereof being spaced longitudinally of the other and provided with an inwardly directed flange 30 having openings 20 31 through which tie rods 32 project. The heads 29 are held in spaced relation by means of spacing sleeves 33 arranged over the rods 32 between the flanges 30. The ends of the rods 32 are threaded and pass through openings 25 in annular plates 34 forming parts of the articulated coupling 22 and at their ends receive nuts 35 which when tightened down, bind the whole structure together. The lateral portion or flange of each head 29 is 30 provided with a series of slots and openings 36 which accommodate a series of spring steel scrapers 37, each of the latter comprising a curved member, one arm of which is attached to the lateral flange by having its extreme end 35 bent at right angles and inserted in a slot 36 to prevent side twisting, a screw being arranged in the arm forward of the end and inserted into the hole or opening 36 in line with the said slot, and which projects rearwardly, while the other arm is directed outwardly in yielding contact with the surface 40 of the pipe. The scraper heads 29 are arranged so that scrapers of adjacent heads are staggered and the free ends of the scrapers 45 37 are flared as illustratively exemplified in Figures 2 and 3.

The first section A is the rotor, and disposed about the periphery of the tubular portion 11 between the last pair of scraper heads 50 29 is a ring 38 mounted on the tie rods 32. The ring 38 carries a channel ring 39 having the open side arranged against the ring 38, the outer side wall of the channel being shorter than the inner side wall so as to leave 55 an annular slot entirely around the arrangement. Into this slot the angular ends of steel fingers 40 are inserted and attached, while the mid portions of the fingers are curved outwardly and inwardly to brush 60 against the surface of the pipe. The fingers are directed towards the rear of the machine and their free ends are turned back upon themselves to engage over the outer edge of a rubber cuff 41 resting against the inner surfaces 65 of the fingers as illustratively exemplified

fied in Figure 1. The combination of the fingers and rubber cuff 41 forms a soft piston ring which makes a spring fit against the interior wall of the pipe.

The trailing end of second section B is provided with a deflecting plate 42 which is a disc shaped member having marginally disposed openings to fit over the rods 32 and against the spider connection 27 and a central opening to accommodate the spring casing 18 therethrough. When the nuts 35 are tightened down over the rods 32 and against the deflecting plate 42, the latter becomes a rigid part of the trailing section B so that the 70 water under pressure directed in the direction of the plate will be deflected outwardly and around the end head 29.

In operation, the water flows through the tubular casing 11 and outwardly through the channels formed by the curved blades or vanes 12 and cover 13. The entire machine is made to rotate slowly by the action of the head of water against the vanes 12 and forced or pushed ahead by the pressure of the water 80 against the soft piston ring 40. The matter scraped from the sides of the pipe is picked up in the whirling water and kept in constant suspension while being carried onwardly from in front of the machine.

In order to prevent independent rotation 90 of either the front or rear sections, I provide means in the form of a projection 43 attached at one end to a leg of the end plate 34, the opposite free end of the projection being projected into the space between adjacent legs 100 of the end plate 34 of the leading section A.

Having now described my invention what I claim and desire to secure by Letters Patent, is:

1. In a pipe cleaner, the combination of a 105 sectional rotor having scraping elements arranged peripherally thereof, the leading section comprising a tubular shell terminating in a forward flared end provided with curved vanes against which a head of water is directed to rotate the sectional rotor and set up a whirling action of the water in advance of the cleaner, a cover for the vanes, and yielding means from the cover to the rearward end of the trailing section to hold the sections 110 in line and the cover in place.

2. A pipe cleaner, as claimed in claim 1, in which the tubular shell is provided with spaced circumferentially disposed openings, and a sleeve valve adjustably arranged over 115 said openings to govern the amount of leakage water passing through said openings.

3. A pipe cleaner, as claimed in claim 1, in which the yielding means connecting the sections comprises a cable disposed axially of the sections, means for engaging one end of the cable to the cover so as to draw the cover toward the vanes, a tubular casing through which the other end of the cable projects, a clamp holding the latter end of the cable in 125

a loop and slideable longitudinally of the casing, a spring under tension disposed between the clamp and the leading end of the casing.

4. A pipe cleaner, as claimed in claim 1, in which the yieldable means connecting the sections comprises a cable disposed axially of the sections, means for engaging one end of the cable to the cover so as to draw the cover towards the vanes, a tubular casing through which the other end of the cable projects, a clamp holding the latter end of the cable in a loop and sliding longitudinally of the casing, a spring under tension disposed between the clamp and the leading end of the casing
- 10
- 15 to adjust the tension on said spring and a collar screwed over said spring casing, and means forming a seat for the collar and having means to prevent rotation of the casing when the collar is adjusted to alter the tension of said spring.

5. A pipe cleaner, as claimed in claim 1, in which the bands of scrapers are spaced longitudinally of the sections, the scrapers projecting rearwardly and then radially to engage

- 25 the inner surface of the pipe being cleaned.
6. A pipe cleaner, as claimed in claim 1, in which the bands of scrapers are spaced longitudinally of the sections, the scraper projecting rearwardly and then radially to
- 30 scrape against the inner surface of the pipe being cleaned, and a yielding piston ring band carried by the said shell of the first section and comprising a series of juxtaposed spring fingers projecting rearwardly in a curve to brush the inner surface of the pipe.

7. A pipe cleaner, as claimed in claim 1, in which the bands of scrapers are spaced longitudinally of the sections, the scraper projecting rearwardly and then radially to scrape

40 against the inner surface of the pipe being cleaned, and a yielding piston ring band carried by the said shell of the first section and comprising a series of juxtaposed spring fingers projecting rearwardly in a curve to brush the inner surface of the pipe, and a cuff placed in the concave channel formed by the surfaces of the spring fingers to hold the water directed against it.

8. A pipe cleaner, as claimed in claim 1, in which the cover comprises a conically shaped wall, the apex thereof receiving one end of the yielding connecting means and the base having a flange in the form of a truncated cone to guide the cleaner at its leading end.
- 55
9. A pipe cleaner, as claimed in claim 1, including spaced rows of scraper heads supporting said scrapers and arranged along the sections, spacing members for holding the heads in spaced relation and tie rods projecting through aid heads and rods to connect them to the section.

10. A pipe cleaner, comprising a rotary section, annular heads of angle metal, one flange thereof being radially disposed and

65 connected to the section, the other flange be-

ing laterally directed and provided with slots and holes, and a series of spring steel scraper fingers mounted on the lateral flanges in the slots and holes thereof and provided with outwardly directed ends having side wings, the scrapers of each head being mounted in alternate forward and rearward positions to bring alternate wings directly behind the wings of the leading scrapers.

11. A pipe cleaner, as claimed in claim 1, in which the tubular shell is provided with means governing the amount of leakage water passing through the cleaner.

In testimony whereof I affix my signature.
